ARC CHUTE

William M. Scott, Jr., Bryn Mawr, Pa., assignor
to I-T-E Circuit Breaker Company, Philadelphia, Pa., a corporation of Pennsylvania

Application January 12, 1945, Serial No. 572,554

3 Claims. (Cl. 200—144)

1

My present invention relates to circuit interrupters and more particularly to a novel arc quencher therefor comprising a plurality of spaced plates of insulating material arranged above and parallel to the arc, the said plates being intersected by a number of transverse metallic rods.

This application is a continuation in part of application Serial No. 550,179, filed August 19, 1944, and relates specifically to a special arrangement of the transverse metallic rods so that they are closer together at the upper portion of the arc chute and so that they are more closely spaced along the back and front regions of the arc chute. Thus, the distance between the transverse metallic rods is decreased as the distance from the point of initiation of the arc increases.

In the construction and operation of circuit interrupters, it is frequently necessary to provide means for extinguishing quickly the arc which is drawn between the contacts as they separate. Such circuit interrupters, which may be tripped open on the incidence of high currents, comprise a pair of main contacts (to carry the full current during normal operation), which are arranged to make after and break before a pair of parallel arcing contacts so that any arcing which may occur will not pit or otherwise destroy the contact surfaces of the main contacts.

The arc which is drawn between the arcing contacts when they separate under over-current conditions is blown upwardly by blow-out means, such as a magnetic blow-out or air blast (both well known in the art) into an arc chute which is arranged to quench the arc by lengthening the same or cooling it, by a combination of these methods or in any other ways.

Arc chutes having spaced insulating plates to lengthen the arc or squeeze the arc into narrow slots are well known. Arc chutes which consist of spaced metallic plates or their equivalent which break the arc up into a number of small arcs in series and move the arc rapidly across cooling surfaces, are also well known.

My prior application Serial No. 550,179 contemplated as its essential function the provision of an arc chute which utilized both the principle of spaced insulating plates to lengthen and squeeze the arc, together with a series of metallic surfaces formed by a series of transverse pins, each of which extends through all of the insulating plates and which are so arranged that the arc is brought into contact therewith and broken up into a series of small arcs and cooled.

The specific improvement and object of my present invention is the arrangement of these

2

transverse pins so that they will be progressively more closely spaced as the distance from the contacts between which the arc is initially drawn is increased.

5 A corollary object of my invention is the provision of means in connection with such a spaced plate transverse pin arc chute for moving the arc readily into the chute and then rapidly cooling and extinguishing the same.

10 Another object of my invention is the provision of novel arc chute extinguishing plates.

These and many other objects of my invention will become apparent in the following description and drawings in which:

15 Figure 1 is a cross-sectional view taken on line 1—1 of Figure 2 looking in the direction of the arrows.

Figure 2 is a front view of the elements of the arc quencher taken from line 2—2 of Figure 1.

20 Referring now to Figures 1 and 2, there is here shown an arc quencher 20 having generally the construction and operation of the arc quencher shown in my Patent No. 2,348,228, dated May 9, 1944, assigned to the assignee of the present invention. The arc chute 20 comprises a pair of side supporting plates 21, 21 of insulating material, between which are mounted a number of spaced arc extinguishing plates 23, 24, 25, 26, 27, also of insulating material. The plates are integrated as a single unit by the transverse rivets 30 and 31 which are provided with insulating bushings 35.

25 Rivets 30 and 31 are also provided with individual insulating washers or spacers 37 to maintain the spacings between the insulating plates.

30 The side plates 21, 21 also carry between them on the transverse bolt 44 the back arcing horn 45; and on the transverse bolts 40 and 41 the front arcing horn 42 and its extension 43.

35 Current enters the circuit breaker, which is here shown in fragmentary view, through the stud 60 and passes to the main stationary contact 61 to the main movable contact 62 mounted on the movable contact arm 63. Appropriate means, such as pigtail connections or other members, may be utilized to carry the current from the main movable contact 62 into the opposite back connection stud, not shown.

40 The contact members are so arranged that the main movable contact 62 will separate from the main stationary contact 61 before the movable arcing contact 65 separates from the stationary arcing contact 66. When the main contacts 61 and 62 have separated, current flows from the stud 60 through the angle member 68 to the sta-

tionary arcing contact 66, which is situated at the lower end 69 of the back arcing horn 45, then to the movable arcing contact 65, which is carried by the movable contact arm 63, and then through a pigtail or other suitable connection to the opposite terminal, not shown.

As the arcing contacts 66 and 65 separate, an arc is drawn therebetween and is transferred to the arcing horns 45 and 42 by suitable blow-out means, preferably magnetic, which are well-known in the art. Since such blow-out means are so well known, they are not here shown but may comprise the blow-out means shown in my application Serial No. 550,179 or in my Patent No. 2,348,228.

When the arc is blown up on the arcing horns 45 and 42, the current path is from the stud 60 through the angle member 68, the lower end 69 of the arc horn 45 to the arc horn 45, then across the arc to the arc horn 42 through the extension 43 of the arc horn 42 to the connecting member 70, to which a pigtail 71 is connected, in order to permit current to flow to the opposite terminal of the circuit breaker.

The arc extinguishing plates 23 through 27 are here shown as substantially V-shaped plates, the lateral edges 80 of which substantially parallel the principal portions of the arcing horns 45 and 42, and the lower ends 81 of which are convexly rounded at the region first presented to the arc. The plates 23 to 27 are not directly in contact with the arcing horns but a small space 82 is left between the edges of the plates and the arcing horns on each side.

The arc quencher 20 is particularly characterized by a large number of transverse copper pins 100, 100 which pass through perforations in the plates 23 through 27, as shown in Figures 1 and 2, and which are supported by the plates 23 through 27. The pins preferably do not contact the opposite supporting insulating members 21—21. This will facilitate assembly and adjustment of the unit, permits the pins to be brought down close to the contacts which form the arc, removes the possibility of breakdown or creepage along the supporting plates 21, 21. The remainder of the structure shown corresponds to the circuit breaker shown in my Patent No. 2,348,228.

The particular advantages of the transverse copper pins 100 have been specifically described in my application Serial No. 550,179 above referred to, and my theory of the specific operation of these pins to obtain extremely fast arc extinguishment has also been set forth therein.

The specific contribution of the present invention, apart from the novel extinguishing plate shown is the staggering of the pins 100. Thus, pins 100a are relatively widely spaced from each other. Pin 100a' is arranged at the very center of the lowest portion of the arc chute in order to intercept the arc and break it serially into two substantially equal arcs. As the arc moves up to the position indicated by the dotted line A, pins 100a² and 100a³ will also intercept the arc, and the arc at this instant should be broken serially into substantially four arcs in series.

As the arc is moved up once more, one of the four series arcs of arc A will move into engagement with one of the pins 100b. The arc will then have the approximate form shown by the dashed line B of Figure 1. As the arc moves upwardly, arc B may then pass from the arc horn 42 to the pin 100a³, to the pin 100b¹, to the pin 100a², to the arc horn 45.

As the arc is blown up still more, it may intercept still other pins and thus in a third position assume the condition shown by line C. In this case, the small arc between pins 100b¹ and 100b² has been intercepted by pin 100c² and the small arc between pin 100a³ and arc horn 42 has been intercepted by pin 100b² so that the arc C now passes from the arc horn 42 to pin 100b², then from pin 100c², then to pin 100b¹, and so on, as shown in the figure.

As the arc moves upwardly again to the position shown, for instance, at D, more pins are intercepted and the short series arc are much smaller. The short arcs are at all times subject to the blow-out which causes the arc as a whole to rise. But, it will be seen that the shorter arc may tend to resist further upward movement, since that would require undue lengthening thereof. Accordingly, the upper pins 100d are much more closely spaced than the lower pins 100a and the spacing of the pins is progressively lessened, as noted, so that the top-most pins 100e are separated by much less than half the distance between the pins 100a. By this means, therefore, as the number of the arcs in series is increased and as the length of these arcs becomes relatively smaller, the spaces between the pins is progressively decreased so that a greater number of pins is introduced in series with the arcs, the number of arcs is increased, and the cooling effect described in application Serial No. 550,179 is greatly enhanced.

Not only are the upper pins 100e progressively more closely spaced than the lower pins, but also I have found that a lateral progressive spacing is desirable. Thus, the pins in the line 100f progressively approach the pins in the line 100g, as these lines of pins approach the top of the arc chute. This is of value since the arc, when it is drawn, generally arches upwardly at the center, as suggested by the arc position shown at E, and a closer spacing of the pins adjacent the arcing horns permits this upwardly arched position of the arc to be assumed; that is, the portions of the arc at position E, which are adjacent to the arcing horns 42 and 45, are downwardly directed, and the close positioning of the pins adjacent to the arcing horns 42 and 45 permits the spacing of the pins to be somewhat similar with respect to arc E at the portions of the arc adjacent the arcing horns 42 and 45.

By this structure, therefore, the arc is first squeezed into one or more slots which extend parallel to the arc path and into which the arc as a whole is squeezed between insulating plates. When squeezed into the slots between these insulating plates, the arc encounters a large number of spaced transverse pins. These pins break the arc up into a series of small arcs between them and, by reason of the rapid movement of the arc with respect to the surfaces of these pins and upwardly from pin to pin, tend to cool the roots of the small series arcs. This tends quickly to extinguish the arc.

Furthermore, since each pin extends through all of the slots, there is a tendency for the current to flow along the pins and for a small arc to strike over between closely adjacent pins of another slot when the arc roots are torn from the same pins in the original slot, thus forming some of the series arcs in a cooler slot, again rendering the arcs highly unstable and tending quickly to extinguish them.

This combination of squeezing the arc between insulating plates, intercepting the arc by metallic

members or pins, breaking the arc up into a plurality of small arcs in series with each other and causing some of the small arcs to strike over in adjacent slots, results in a very quick extinguishing action.

Moreover, by staggering the pins 199 so that they are more closely spaced toward the top of the arc chute and more closely spaced adjacent the arcing horns, I increase the pulling action of the pins where it is most effective, when the arc has been stretched to the point where it may most readily be extinguished.

The lower pins which are widely spaced break the arc up into a series of arcs progressively, that is, pin 198a which first breaks the arc into two arcs in series, then when pins 198a² and 198a³ are encountered, the arc is broken into four arcing series. Thus, the movement of the arc upwardly in the chute is not impeded by the pins, since the arc does not first encounter a great number of pins which would offer substantial back pressure and create substantial turbulence through the arc and the arc gases.

As the arc has been moved up into the chute to a point where it has been substantially attenuated and partially cooled, then the number of pins which it strikes is progressively increased not only by the widening of the chute but also by the closer spacing of the pins so that the arc is at this point subjected to substantial turbulence and to increased cooling action, while, at the same time, it is squeezed between the insulating plates. In this way, I make it possible for any arc to move readily upward into the arc chute without any substantial back pressure, and once it has moved upwardly and been attenuated to a sufficient degree, I introduce additional cooling means which will rapidly extinguish it. It is obvious, of course, that on the extinction of any one of the arcs in series in the upward portion of the chute, the arc as a whole will go out.

In the foregoing, I have described my invention only in connection with a specific preferred embodiment thereof. Many variations and modifications of my invention should now be obvious to those skilled in the art. Accordingly, I prefer to be bound not by the specific disclosures herein but only by the appended claims.

I claim:

1. An arc chute comprising means for drawing an arc; means for moving the arc into the chute; and arc extinguishing means within the arc

chute; said arc extinguishing means comprising plurality of spaced metallic members arranged in staggered relation in successive vertical rows and arranged transverse to the path of movement of the arc in the chute; said metallic members being relatively more widely spaced at the portions of the arc chute which the arc first enters and being relatively more closely spaced at the portions of the arc chute remote from the portion which the arc first enters, and having varying spacing in a horizontal direction.

2. An arc chute comprising means for drawing an arc; means for moving the arc into the chute; and arc extinguishing means within the arc chute; said arc extinguishing means comprising plurality of spaced metallic pins arranged in staggered relation in successive vertical rows and arranged transverse to the path of movement of the arc in the chute; a plurality of arc splitters, said metallic pins being supported through perforations in said arc splitters and being relatively more widely spaced at the portions of the arc chute which the arc first enters and being relatively more closely spaced at the portions of the arc chute remote from the portion which the arc first enters, said pins being in rows, the spacing between the rows being different from each other.

3. An arc chute comprising means for drawing an arc; means for moving the arc into the chute; and arc extinguishing means within the arc chute; said arc extinguishing means comprising plurality of spaced metallic pins arranged transverse to the path of movement of the arc in the chute; said metallic pins being relatively more widely spaced at the portions of the arc chute which the arc first enters and being relatively more closely spaced at the portions of the arc chute remote from the portion which the arc first enters; said metallic pins being in rows, the spacing between the rows being different from each other.
